UNITED STATES PATENT OFFICE.

OLE O. STORLE, OF TACOMA, WASHINGTON.

REVOLVING VALVE FOR GAS ENGINES.

Application filed November 13, 1926. Serial No. 148,193.

My invention relates to the valve mechanism of gas combustion engines for automobiles and other motor driven vehicles. It has for its objects, first, to provide within 5 each head of a gas engine, a revolving valve wherein are ports for gas intake and exhaust outlets, these ports being so timed and adjusted as to operate through corresponding fixed ports in the walls of the cylinder heads; second, to provide positive and noiseless valves for gas engines without the use 10 of spring actuated mechanism; third, to provide adjustable means whereby said sleeve valves can be made gas tight, and fourth, 15 to provide a geared mechanism between the crank shaft of the gas engine and said revolving valve whereby the same will be operated with positive regularity.

I attain these objects by means of the 20 mechanism illustrated in the accompanying drawing in which—

Fig. 1 is horizontal top view of a pair of engine cylinder heads on the line 1—1 with the inclosing cap of the cylinders removed. 25 Figure 2 is a vertical cross section of one of the engine cylinders continued down through the crank case of the engine.

Similar characters refer to similar parts of each figure.

30 Referring to the drawing, Fig. 1 represents a top view of the usual form of a gas engine with two or more cylinders, only two cylinders 1 and 2 being indicated, and at one side of which an exterior view 3, is shown of the gas supply and exhaust channels indicated therein by broken lines. Fig. 35 1 is taken on the line 1—1 of Fig. 2 and shows the gear wheel mechanism by which the revolving valve is operated for a four 40 cycle engine.

The construction and operation of my invention is more clearly set forth in Fig. 2, which is a vertical cross section through line 2—2. The construction and operation is the 45 same in each of the two cylinders and likewise in engines where two or more pairs of cylinders are combined and operated on one crank shaft.

50 My improvement comprises a new form of cylinder head 4 made on the top of the cylinder body 5. The cylinder head and body are each made with inner and outer walls, leaving an open space 6 between for the circulation of a water cooling system 55 common to gas engines. The cylinder head 4 is tapered upwardly like the frustum of a

cone and is designed to have a revolving valve with a corresponding frustum shaped interior fitted and operated thereon, as indicated at 7—7. The outer surface of this 60 revolving valve has a vertical cylindrical exterior and is surrounded by a neatly fitted outer casing 8 which forms an outer wall enclosing the revolving valve and frustum shaped cylinder head. The outer casing is 65 securely attached to the cylinder body 5 as indicated at 9.

A gas intake port 10 is made through the side of the frustum shaped cylinder head 4. In alignment therewith, port 11 is made 70 through the outer casing 8 and connected with the gas supply channel 3. On the opposite side of the cylinder is made an exhaust port not seen in the drawing but indicated under character 12 in Fig. 1, that is 75 connected with the exhaust channel designed for it.

In the side of the cylindrical revolving valve 7 is a port opening 13 so adjusted and timed as to pass in alignment with the ports 80 10 and 11 to admit gas when required and with the port 12 at proper time for exhaust.

The cylindrical valve 7 is revolved by an annular gear 14 extended from its top end. It is made gas tight on its vertical exterior 85 by a packing ring 15 contacting the outer casing 8. The frustum shaped interior is held in neat fitting adjustment with the frustum shaped cylinder head 4 by means of an annular plate 16 on the annular gear 90 extension 14 of the revolving valve 7. The cylinder head casing 8 is inclosed with a cap or cover 17 fixed thereon. In this cap 17 are set screws 18 designed to bear on the annular plate 16. These screws 18 are to be 95 so set that the revolving valve will be held in neat fitting adjustment with its frustum shaped cylinder head, then each is fixed with lock nuts 19 screwed tight on the head cap 17. Should the revolving valve become loose 100 or worn from use, it can be readjusted by resetting the set screws 18. The annular plate is held from revolving with the valve by raised lugs on each side of the set screws as will be seen in the drawing.

105 The revolving valves with their attached annular gears are made to revolve in unison with the crank shaft in a novel manner. In one of the crank cases a gear 20 is mounted on the crank shaft 21. This gear 20 engages 110 a like gear 22 mounted on a shaft 23 running parallel with the crank shaft. On this shaft

23 is mounted a miter gear to engage and operate a like miter gear 24 mounted on a vertical shaft 25 parallel with each of the two cylinders and centered on a line midway between each, as indicated in Fig. 1, and as partially shown in Fig. 2. At the top of this vertical shaft 25 is a gear 26 so mounted as to engage and operate the annular gear 14 on the two cylinders adjacent to it and their respective revolving valves. The gear 26 is so proportioned with the gears 14 as to make two revolutions to their one as required for a four cycle gas engine.

It will be seen that my invention is designed to be constructed on mechanical lines that are practical, simple and economical. The revolving valve can be adjusted, timed and fitted to operate with perfect nicety. The parts are easy to make and assemble. All is securely housed to keep free from dust and injury. The valves operation will be positive and noiseless with a minimum of wear and cost of upkeep. The spark plug is to be fixed into the threaded opening 27 and the manifold is to be attached on the cylinder head in the usual manner with a bolt at 28.

The revolving valves with their operating mechanism are effectively lubricated by a circulating oil pipe 29 above the cylinder heads with an outlet onto the top of each as shown in Fig. 2. This will keep the annular bearing plate, the top of the revolving valves and the operating gears bathed in oil and each will be effectively lubricated. A small groove 30, in the side of the incase-

ment of the vertical shaft 25 will allow the surplus oil to slowly return to the crank case of the engine.

It is to be observed that the drawing is 40 designed to set forth the constructive and operative features with the novel combinations involved therein. The size and proportion of any part may be varied to secure the most perfect and effective operation. 45

Having described my invention, I claim—

In a four cycle gas engine with duplex cylinders as described, the combination of a frustum shaped head on the explosive end of each of said cylinders, an attached outer 50 casing enclosing each of said heads, said heads and outer casings having ports in alinement and connection with the channels of gas supply and exhaust, a cylindrical revolving valve so formed and operated as to 55 revolve in neat fitting adjustment between the said heads and outer casings and in timed relation with said ports, an annular bearing plate on the top edge of each of said revolving valves, an encircling cap 60 fixed on the top of said outer casing with lock nut set screws therein to bear on said annular bearing plate between the lugs thereon to hold said revolving valve in neat fitting adjustment as described, and said 65 encircling head cap forming an oil bath chamber above said valve and operating mechanism and a circulating pipe oil system to supply oil into said oil bath chamber for effective lubrication.

OLE O. STORLE.
